CLAIM

The ornamental design for a packaging as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front plan view of the packaging in a flat unwrapped state showing our new design; and, FIG. 2 is the packaging of FIG. 1 in a wrapped state, showing the packaging in use.

**1 Claim, 2 Drawing Sheets
(2 of 2 Drawing Sheet(s) Filed in Color)**

FIG. 1

FIG. 2
